TELEPHONE-CALL-LOCATING SYSTEM.

1,183,821.

Specification of Letters Patent. Patented May 16, 1916.

Application filed December 6, 1906. Serial No. 346,547.

To all whom it may concern:

Be it known that we, TALBOT G. MARTIN and JOHN ERICKSON, both citizens of the United States of America, and residents of 5 Chicago, Cook county, Illinois, have invented a certain new and useful Improvement in Telephone-Call-Locating Systems, of which the following is a specification.

Our invention contemplates the provision 10 of means for locating calls in an automatic telephone exchange system. For example, suppose some subscriber complains that someone is continually calling him up and annoying him. In such case, our call-locating device locks the connector on the called line as soon as the latter is called, and prevents a release of the connection between the two lines. Thus all calls coming onto the complaining subscriber's line can 15 be traced until the call complained of is finally located. With this arrangement an alarm or signal is preferably given as soon as the line to which the call-locating device has been applied is called. It will be understood, of course, that our call-locating device can be temporarily applied to the line 20 of any subscriber who wishes calls to be traced. When the central station attendant gets the signal he immediately traces 25 the connection back to the calling line. Other uses will be obvious and will occur to those skilled in the art.

The accompanying drawing shows diagrammatically two substations #500 and 35 #220 connected by means of central office automatic switching apparatus involving our invention. In the said office the calling substation #500 has allotted to it the first-selector A of the type described in United 40 States Patent No. 815,321, granted March 13, 1906, to Keith, Erickson and Erickson. It will be noticed that the central battery B has its positive terminal preferably grounded. The operating relays of the central 45 switches are normally connected to the non-grounded terminal of said battery, so that the subscriber by grounding his line conductors may operate the said switches, as is usually the custom in systems of the class 50 in connection with which we have elected to illustrate our invention. In addition to the said first-selector there is shown at the central office a connector C which is an im-

provement on the connector disclosed in United States Patent No. 815,176, granted 55 March 13, 1906, to Keith, Erickson and Erickson, and another first-selector D allotted to the called line. The connector C is the same as the patented connector, except that the release magnet terminal 60 (which, in the said patent, is connected directly with the battery lead) connects with the battery lead through two contact springs which are controlled by a relay in the private wiper circuit, so that when the side 65 switch of the connector is in third position, the private wiper instead of being connected directly to ground is in this case connected to ground through the said relay. Furthermore, the middle spring (controlled by the 70 back-bridge relays M) of the said patent is omitted from the connector of our invention. The first-selector D is exactly like the first-selector A, with the addition of the relay and vibrating bell shown at H, which 75 constitute a part of the selector D and which may be attached to any first-selector in the central office. At E is shown a ring generator and at F a busy signaling machine.

The substation #500 may be of any suitable 80 type and, as shown, comprises a receiver 2, switch-hook 3, induction-coil 4 which consists of the primary winding 5 and secondary winding 6, transmitter 7, ringer 8 and battery 9. In addition to the above-mentioned parts there is provided an impulse wheel 10 which has the usual vertical impulse teeth 11 that are adapted to operate the vertical impulse spring 12 for sending ground impulses to one side of the line. 90 The impulse wheel also carries the rotary impulse tooth 13 which operates the rotary impulse spring 14 for grounding the rotary side of the line. The said impulse wheel is rigidly connected to the same shaft to which 95 the substation dial is secured. The switch-hook has radiating from its body a number of cam arms 15, 16 and 17 and is pivotally secured to the keyboard. The cam arm 15 controls the so-called locking arm 18 100 which is used to lock the dial while the receiver is on the hook. When the coöperating ground springs 19 and 20 engage, the ground post 21 is then connected to the substation ground G'. The cam arm 16, when 105 the switch-hook is down, maintains a con-

tact with the spring 22, thereby bridging the ringer 8 across the line. The springs 23 and 24 are then disengaged, and the primary circuit including the primary winding 5, transmitter 7 and local battery 9 is interrupted. Furthermore, when the switch-hook is down the springs 32 and 33 are disengaged; but when the receiver is removed from the switch-hook the said springs engage, thereby bridging across the line the secondary circuit.

The signaling device whereby a subscriber may signal another after connection has been established comprises a push button 25 and a spring 26 which normally engages the contact point 27; but when the button 25 is pressed the spring 26 leaves the contact point 27 and engages the contact point 28, which latter is connected with the substation ground G'. Means whereby the subscriber may release the central station apparatus brought into service comprises three springs 29, 30 and 31 known as the release springs, and so controlled by the cam arm 17 that when the switch-hook descends the three release springs are brought into contact, thereby grounding both of the subscriber's line conductors simultaneously. If the subscriber at substation #500, for example, wishes to call the subscriber at substation #220 he first removes the receiver 2 from the switch-hook 3, thereby placing the substation ground G' in connection with the ground post 21, through the coöperating ground springs 19 and 20. The calling subscriber in making a call operates his dial once for each digit of the desired number. On the return motion of the dial, at each operation, first the vertical impulse teeth engage the vertical impulse spring 12, and then the rotary impulse tooth engages the rotary impulse spring 14, forcing said springs into contact with the ground post 21 and as a result grounding the vertical and rotary line conductors 34 and 35, respectively. After the first digit is called the first-selector-shaft wipers 36, 37 and 38 are raised to the second level of the line and private banks as follows: When the spring 12 engages the ground post 21 an energizing circuit is established through the vertical relay 39 of the first-selector A. The current in this circuit flows from ground G' through the springs 20 and 19 to the ground post 21, thence to the vertical impulse spring 12, vertical line conductor 34, side switch wiper 40, contact point 41, vertical line relay 39, through the bridge-cut-off springs 42 and 43 to the battery lead 44, thence through battery B and to ground G. Each time that the vertical line relay 39 is energized the springs 45 and 46 are pressed into engagement, and an energizing circuit is established through the vertical magnet 47. The circuit through the

springs 45 and 46, private magnet springs 49 and 48, vertical magnet 47 to the battery lead 44, thence through battery B and to ground G. The vertical magnet being operated twice the first-selector switch shaft and wipers 36, 37 and 38 are carried to a level with the contact points that constitute the terminal of the trunk line leading to the connector C. Following the vertical impulses the rotary impulse spring 14 comes into contact with the ground post 21, thereby grounding the rotary line conductor 35 once and energizing the rotary line relay 50 of the first-selector once. The path of the energizing circuit may be traced as follows: from the substation ground G' through the springs 20 and 19 to the ground post 21, rotary impulse spring 14, rotary line conductor 35, side switch wiper 51, contact point 52, rotary line relay 50, bridge-cut-off springs 53, 42 and 43 to the battery lead 44, thence through battery B and to ground G. The rotary line relay 50 upon energizing closes the springs 54 and 45 in contact, thereby closing an energizing circuit through the private magnet 55 which extends from ground G' through the springs 45 and 54, private magnet 55 to the battery lead 44, thence through battery B and to ground G. The private magnet 55 being energized for a moment, the side switch of the first-selector A passes from first to second position, thereby permitting the side switch wiper 56 to engage the contact point 57, thus closing a circuit through the rotary magnet 59. The current-flow is from ground G' to the contact point 57, side switch wiper 56, through the interrupter springs 58, thence through the rotary magnet 59 to the battery lead 44, and through battery B to ground G. The rotary magnet is energized over this circuit and operates to carry the shaft wipers 36, 37 and 38 into engagement with the first set of bank contacts of the second level that, it is assumed, constitutes the terminals of the connector switch C. But if the first trunk line is busy, assuming that the trunk leading to the said connector leads off from the first set of contacts of the second level, it is protected, as is well known, by a positive guarding potential, and an energizing circuit is established through the private magnet 55 when the private wiper 38 strikes the grounded private bank contact, thereby retaining the side switch in second position and maintaining the energizing circuit through the rotary magnet 59 in a well known manner. However, as soon as the private magnet is deenergized, the side switch is tripped to third position; but if there are no busy contacts to be passed over, as assumed in the first instance, then the rotary magnet 59, as is well known, trips the side switch to third position, with the result that the side switch wipers 40, 51, 56

and 60 engage the respective contact points 61, 62, 63 and 64, thus extending the subscriber's line conductors 34 and 35 to the connector C. Also, since the side switch 5 wiper 60 engages the grounded contact point 64, a guarding potential is established at the private wiper 38, for protecting the seized trunk line from being molested by any other switch.

10 The second digit is called after the subscriber has established connection with the connector C, by sending impulses to the trunk conductors 65 and 66. The subscriber rotates the dial, as described, for the second 15 digit 2, thereby grounding the vertical and rotary line conductors 34 and 35, which causes the energization of the connector vertical and rotary line relays 67 and 68, the former twice and the latter once. The current 20 for energizing the vertical relay 67 flows over the following path: from ground G' through the springs 20 and 19 to the vertical impulse spring 12, vertical line conductor 34, side switch wiper 40, first-selector shaft wiper 36, conductor 65, vertical 25 line relay 67 to the battery lead 44, and through battery B to ground G. Each time that the vertically relay 67 is energized, the line relay springs 69 and 70 are pressed into contact, thereby closing an energizing circuit 30 through the vertical magnet 71 over the following path: from ground G' to the springs 69 and 70, private magnet springs 72 and 73, side switch wiper 74, contact point 75, vertical magnet 71 to the battery lead 44, thence 35 through battery B and to ground G. The vertical magnet is thus energized and operates to raise the shaft and shaft wipers one step at a time until the said wipers are carried 40 two steps to the level in which are located the terminal contacts of the line #220. The impulses to the vertical side of the line being followed by the ground impulse to the rotary side, when the rotary impulse spring 45 strikes the ground post 21, the rotary line relay 68 of the connector becomes energized through the following path: from ground G' to the springs 20 and 19, ground post 21, rotary impulse spring 14, rotary line conductor 35, side switch wiper 51, shaft wiper 37, trunk conductor 66, rotary line relay 68 50 to the battery lead 44, thence through battery B and to ground G. The energization of the rotary line relay 68 causes the energization of the private magnet 76 over a circuit extending from ground G' through the springs 69 and 77 to the private magnet 76 and to battery lead 44, thence through battery B and to ground G. As a result the 55 connector side switch and wipers 78, 79, 80 and 74 are released from first to second position. The last digit being naught, the subscriber operates the dial as previously described, grounding the vertical line conductor 34 ten times and the rotary line con-

ductor 35 once. The vertical and rotary line relays 67 and 68 are operated over previously traced circuits. However, when the line relay springs 69 and 70 engage, a circuit is closed through the rotary magnet 81 70 instead of through the vertical magnet 71. The energizing circuit extends from ground G' through the line relay springs 69 and 70, private magnet springs 72 and 73, side switch wiper 74, contact point 82, rotary magnet 81 to the battery lead 44, thence 75 through battery B to ground G. Each time that the rotary magnet is energized it rotates the shaft wipers 83, 84 and 85 one step at a time until the said wipers are carried 80 into engagement with the normal conductors 86, 87 and 88 that lead to the called subscriber's line.

The energization of the rotary line relay 68, as previously stated, completes an energizing circuit through the private magnet 76 which now operates with one of two results, namely the release of the side switch from second to third position and the establishment of connection between calling and 85 called lines, if the latter is not busy; or the so-called busy release of the connector if the called line is busy, which releases is brought about as follows: If the called line is busy a guarding potential appears at the private 90 bank contact into engagement with which the private wiper 85 has previously been rotated; then when the private magnet 76 energizes as a result of grounding the rotary 95 line conductor 35, as explained, the private 100 springs 132' and 133' are brought into contact while the side switch wiper 80 is in second position, with the result that an energizing circuit is established through the release magnet 100 over the following 105 circuit: from the grounded private bank contact to the private wiper 85, thence through the relay 90, side switch wiper 80, contact point 89 to the private springs 133' and 132', thence through the release 110 magnet 100 and through the springs 99 and 98 to the battery lead 44, thence through battery B to ground G.

It will be observed that although the current in this release circuit passes through 115 the relay 90, the spring 99 controlled by said relay is given sufficient tension to prevent the armature of said relay from being operatively attracted when in series with the release magnet 100, which is ordinarily 120 sixty ohms. The said relay 90 is adapted to operatively energize when connected in series with the battery B through thirty ohms. Therefore, when the release magnet 100 energizes, as explained, the connector 125 switch-shaft and side switch are restored to normal condition, with the result that the line and private wipers 83, 84 and 85 are disconnected from the normal conductors 86, 87 and 88; the private wiper 85, upon dis-

connecting from the private normal conductor 88, destroys the energizing circuit for the release magnet. The connector side switch being thus thrown into first position, 5 then when a calling subscriber presses his signaling button 25 and grounds the vertical line conductor 34 by pressing the spring 26 onto the ground contact 28, he energizes the connector vertical line relay 67 over circuits 10 that have been described. The said relay in turn energizes the vertical magnet 71 in a well known manner, raising the switch-shaft and permitting the off-normal springs 93' and 94' to pass into engagement, as a result 15 closing a busy signaling circuit through the calling subscriber's station, over circuits that are well understood. Upon hearing the busy signal the subscriber, understanding that the desired line is busy, will restore his receiver to the switch-hook, grounding the 20 vertical and rotary line conductors 34 and 35 simultaneously, energizing the line relays 67 and 68 of the connector C simultaneously, and pressing the trunk-release springs 101 25 and 102 into contact. The engagement of said springs establishes an energizing circuit through the release magnet 100 in series with the back-release relay 103 of the selector A, and produces the release of the 30 switches, as will be hereinafter more fully described.

The foregoing is, therefore, an explanation of the result following if the subscriber's line is busy. Considering now the result 35 if the called line is not busy, it will be evident that the side switch passes to third position, thus placing the side switch wipers 78, 79, 80 and 74 in contact with their respective contact points 119, 112, 88' and 104 40 in third position. Furthermore, when the side switch passes to third position a guarding potential is established for protecting the called line. This potential extends from ground G⁵ to the contact point 88', side 45 switch wiper 80, relay 90, switch-shaft wiper 85, which latter engages the private contact of the called line. The said guarding potential closes an energizing circuit through the relay 90 of the connector C, in 50 series with the bridge-cut off relay 91 of the first-selector D. Furthermore, since the relay 92 of the selector D is connected in multiple with the bridge-cut-off relay 91 between the normal conductor 88 and battery B, the 55 relay 92 also becomes energized. This energizing circuit extends from ground G⁵, contact point 88' to the side switch wiper 80, through the winding of the relay 90, private wiper 85, private normal conductor 88, 60 through the normal springs 93 and 94 from whence it divides, one path being through the bridge-cut-off relay 91 to the battery lead 44, and the other path being through the relay 92 to the battery lead 44, thence 65 through battery B and to ground G. The

relay 91 upon energizing removes the bridge formed by the vertical and rotary line relays of the selector D, from across the line. The relay 92 upon energizing operates to close the springs 95 and 96 in contact, whereby a circuit is closed through the alarm bell 97. Said circuit extends from ground G⁵ through the bell 97, springs 95 and 96 to the battery lead 44, thence through battery B and to ground G. The ringing of the bell 70 gives to the attendant an audible signal indicating that the line to which the detecting apparatus is attached has been called by a subscriber. Furthermore, the relay 90 upon energizing operates to disengage the springs 75 98 and 99, thereby disconnecting the release magnet 100 of the connector C from the battery lead 44. Now, when the calling subscriber restores his receiver to the switch-hook, and thereby grounds the vertical and 80 rotary line conductors 34 and 35, thus establishing an energizing circuit through the vertical and rotary line relays 67 and 68, which operate to place the front-release 85 springs 101 and 102 in contact, the release 90 of the central office switches does not occur, because the energizing circuit through the release relay 103 of the first-selector A and of the release magnet 100 is opened between the release magnet 100 and the battery lead 95 44 by the separation of the springs 98 and 99. The central office switches then remain 100 in their operated positions, whereby the attendant may trace the call from the called line at the selector D back to the connector C and then to the selector A, thus detecting the substation from whence the call originated.

In exchanges employing connectors of this type—that is, with the relay 90 in the private wiper circuit extending from the side switch wiper 80 to the private wiper 85—calls may be made and the switches employed may be released in the usual manner, when the detecting device shown at H is not attached to the called line. In that case the current flowing through the relay 90 in series with the bridge-cut-off relay 91 (which is wound to a resistance of fourteen hundred ohms) is not sufficient to operatively energize the relay 90. Therefore, the relays 67 and 68, upon energizing simultaneously 115 when the calling subscriber restores his receiver to the switch-hook, now close an energizing circuit, when the springs 101 and 102 engage, through the release relay 103 and release magnet 100 in series, since the relay 90 does not operate to disconnect the release magnet 100 from the battery lead 44 at the springs 98 and 99.

Returning to the explanation of the calling operation, it should be described that in order to signal the called subscriber, the calling subscriber presses the signaling button 25, placing the spring 26 in contact with 120

the substation ground G' , thereby energizing the vertical line relay 67. The path of the energizing circuit extends from ground G' , contact point 28, spring 26, springs 32 and 33 to the vertical line conductor 34, side switch wiper 40, contact point 61, first-selector shaft wiper 36, trunk conductor 65, vertical relay 67 to the battery lead 44, thence through battery B and to ground G.

5 It will be remembered that the connector side switch has passed from second to third position, and that the side switch wiper 74 is in engagement with the contact point 104, thereby placing the vertical line relay 67 in control of the ringer relay 105 in the same manner in which the rotary magnet 81 came under the control of the vertical line relay 67 when the side switch passed from first to second position. Therefore, when the vertical line relay 67 presses the springs 69 and 70 into contact, the ringer relay 105 is energized by a flow of current from ground G' to the relay springs 69 and 70, private magnet springs 72 and 73, side switch wiper 74, contact point 104 to the ringer relay 105 and to the battery lead 44, thence through battery B and to ground G. The ringer relay upon energizing shifts the springs 106 and 107 from the springs 108 and 109 and onto the springs 110 and 111, respectively. This results in the separation of the calling subscriber's line from the called subscriber's line, and in bridging across the line of the latter the terminals of the ringer generator 35 E. A signaling current is therefore sent from the generator E to the ringer relay springs 110 and 106, side switch wiper 78, contact point 112, connector shaft wiper 84, normal conductor 87, rotary line conductor 40 114 to the ringer 115, springs 116, switch-hook 117 to the vertical line conductor 118, normal conductor 86, connector shaft wiper 83, contact point 119, side switch wiper 78, ringer relay springs 107 and 111 back to the generator E. As soon as the calling subscriber ceases to press the signaling button 45 25 the ringer relay 105 becomes deenergized, and the springs 106 and 107 resume their normal position in contact with the springs 50 108 and 109, respectively. The subscriber at substation #220 in response to the signal removes the receiver 120 from the switch-hook 117, thereby removing the ringer 115 from across his line and bridging the secondary circuit instead, which circuit includes the receiver 120, secondary winding 121 of the induction-coil 122 and the springs 123 and 124. The local transmitter circuit is closed as soon as the springs 125 and 126 engage in contact. The two substations 55 #500 and #220 are now connected over the circuit shown in heavy lines on the drawing.

60 The so-called front-release of the central office switching apparatus occurs when the calling subscriber restores the receiver 2 to

the switch-hook 3, thereby pressing the springs 29, 30 and 31 into engagement for a moment. The contact of the said release springs grounds the vertical and rotary line conductors 34 and 35 simultaneously from ground G' to the release spring 29, thence through the springs 30 and 31 to the vertical and rotary line conductors, causing the energization of the connector line relays 67 and 68, which in turn operate to close a circuit through the relay 103 of the first-selector A in series with the release magnet 100 of the connector C, as follows: The path of the current extends from ground G' to the contact point 64, side switch wiper 60, release relay 103, first-selector switch-shaft wiper 38, connector trunk-release springs 101 and 102, release magnet 100, springs 99 and 98 to the battery lead 44, thence through battery B and to ground G. When the connector release magnet 100 is thus supplied with current it energizes, and as a result the switch-shaft and side switch of the connector are restored to normal position, thus breaking the connection between the connector switch-shaft wipers 83, 84 and 85 and the normal conductors 86, 87 and 88. The back-release relay 103 of the first-selector A, being in the same circuit as the release magnet 100, energizes simultaneously with the latter, and presses the springs 127 and 128 into engagement, which in turn close an energizing circuit through the release magnet 129 of the first-selector A. This circuit extends from ground G' through the release relay springs 127 and 128, through the winding of the release magnet 129 to the battery lead 44, thence through battery B and to ground G. All the relays and magnets thus energized attract their respective armatures, and as soon as the substation release springs 29, 30 and 31 separate and break the ground connection with the conductors 34 and 35, they again deenergize. The calling subscriber thus restores all switching apparatus 110 which he originally brought into use.

65 The back-release or back-bridge relays 135 and 136 are provided in order that the called subscriber may not remain helplessly tied up, so to speak, while the bridge-cut-off relay 91 is energized, when a line is called that is not provided with the attachment H. Should he desire to make an independent call before the calling subscriber releases, he (the called subscriber) may break the established connection and secure control of the first-selector D. After establishing connection between the ground springs 130 and 131 by turning the dial, he may ground the line conductors 118 and 114 simultaneously by 125 restoring the receiver 120 to the switch-hook 117, and thus press the release springs 132, 133 and 134 into engagement. As a result an energizing current will pass through the vertical back-bridge relay 135 and the rotary 130

6 back-bridge relay 136 of the connector C. The circuit through the vertical back-bridge relay extends from the substation ground G⁸ to the ground springs 130 and 131 to the springs 134 and 133, vertical line conductor 118, normal conductor 86, shaft wiper 83, contact point 119, side switch wiper 78, ringer relay springs 107 and 109, vertical back-bridge relay 135 to the battery lead 44, thence through battery B and to ground G. The energizing circuit of the back-bridge relay 136 extends from ground G⁸, release springs 134, 133 and 132 to the rotary line conductor 114, normal conductor 87, shaft wiper 84, contact point 112, side switch wiper 79, ringer relay springs 106 and 108 and rotary back-bridge relay 136 to the battery lead 44, thence through battery B and to ground G. The back-bridge relays 135 and 136 upon energizing simultaneously press the back-release springs 137 and 138 into contact, which completes an energizing circuit to the release magnet 100 from ground G⁹ to the springs 137 and 138, through the release magnet 100, springs 99 and 98 to the battery lead 44, thence through battery B and to ground G. The release magnet is thus energized and the switch-shaft wipers 83, 84 and 85 and side switch 30 are restored to normal position. The energizing circuit through the bridge-cut-off relay 91 is broken when the shaft wiper 85 leaves the private bank contact, and thus the connector switch C is released and the first-selector D is restored to the direct control of substation #220. The subscriber at substation #500 may restore the first-selector A by grounding the line conductors 34 and 35.

40 It is evident from the foregoing that our invention provides a means for locating a subscriber who may be annoying some other subscriber. If complaint is made that a certain subscriber is being annoyed by an unknown party, the detecting device may be connected (as shown at H) to the first-selector allotted to the complaining line; then when any connector of the exchange connects with the said line a circuit is completed which automatically locks the said connector in its operated position, and at the same time another circuit is closed which may either ring a bell or light a lamp, indicating to the attendant that the complaining line has been seized. The attendant 45 may then easily trace the call back from the connector to the calling first-selector and, therefore, determine from which substation the call originated. The attachment H is, of course, movable, but the relay 90 is permanently connected to the private wiper circuit of the connector C.

50 The relay 90 and 92 may be wound to any suitable resistance, but with a central battery of fifty volts good results have been obtained when relay 90 is wound to a re-

sistance of one-half ohm and relay 92 to a resistance of thirty ohms. The reason for winding the relay 90 to about one-half ohm is as follows: If any other connector switch should attempt to call in on a line to which the detecting apparatus H is attached, the said connector would, of course, be automatically released, and the calling subscriber would receive the busy signal when attempting to signal. The current for automatically releasing the connector would be supplied in the well-known manner through the private shaft wiper 85 and side switch wiper 80 of the connector C, except that in this case the current would have to pass through the relay 90, and if this relay were of high resistance the release magnet of the second calling connector would not receive sufficient current to operatively energize it.

55 It will be seen that we provide a call-locating device which can be applied to any line for the purpose of tracing all calls coming onto such line. We also provide a signal which can be individual to a single line and which indicates when the line is called.

60 The connector C can be employed on a percentage basis, thus making them less in number than the subscribers. For example, a group of one hundred subscribers need 95 have only ten connectors for accommodating all calls coming onto their lines. The first-selectors can also be arranged on a percentage basis, in any known or suitable manner. If necessary, second or third selectors may 100 be employed in order to provide automatic trunking in a larger exchange. With the arrangement shown the first-selectors are sufficient for automatically trunking to idle connectors.

65 What we claim as our invention is:—

1. In a telephone exchange system, the combination of telephone lines, connectors less in number than said lines, adapted to make connection with any one thereof, means for automatically trunking a calling line to an idle connector, means for operating said connector, and a call-locating device applied to a certain one of said lines, adapted to coöperate with any calling connector 110 in preventing a release when said certain line is called.

115 2. In a telephone exchange system, the combination of telephone lines, connectors adapted to make connection with any one 120 thereof, means for automatically trunking a calling line to an idle connector, means for operating said connector, and a call-locating device applied to a certain one of said lines, adapted to coöperate with any calling connector 125 in preventing a release when said certain line is called.

3. An automatic connector provided with a release circuit, a relay for opening said circuit, and a call-locating device for caus- 130

- ing the said relay to energize when the connector is used for calling a certain subscriber.
4. An automatic connector provided with release mechanism, a relay adapted when energized to prevent the operation of said mechanism, and means for energizing said relay when the connector is used for calling a certain subscriber.
10. 5. The combination of a group of telephone lines, connectors less in number than said lines, each adapted for connecting with any one thereof, and means applied to one of said lines to non-releasably retain any calling connector thereon.
15. 6. An automatic telephone exchange system provided with a call-locating device adapted to be made temporarily individual to any called subscriber thereof, to prevent disconnection between the subscribers, provided with means for giving a signal.
20. 7. In a telephone system divided into groups, the combination of telephone lines, connectors less in number than said lines, adapted to make connection with any one thereof, means for automatically trunking a calling line to an idle connector, means for operating said connector, and a call-locating device applied to a certain one of said lines,
25. 30. adapted to coöperate with any calling connector in preventing a release when said certain line is called, said connectors having one motion to select groups and another motion to find the called line in any selected group.
35. 8. In a telephone system divided into groups, an automatic connector provided with a release circuit, a relay for opening said circuit, and a call-locating device for causing the said relay to energize when the connector is used for calling a certain subscriber, said connector having one motion to select groups and another motion to find the called line in any selected group.
40. 9. In a telephone system divided into groups, an automatic connector provided with release mechanism, a relay adapted when energized to prevent the operation of said mechanism, and means for energizing said relay when the connector is used for calling a certain subscriber, said connector having one motion to select groups and another motion to find the called line in any selected group.
45. 55. 10. In a telephone system divided into groups, the combination of a group of telephone lines, connectors less in number than said lines, each adapted for connecting with any one thereof, and means applied to one of said lines to retain any calling connector thereon, said connectors having one motion to select groups and another motion to find the called line in any selected group.
50. 60. 11. An automatic telephone exchange system having lines divided into groups, hav-
- ing means for selecting the groups by vertical motion and the lines by rotary motion, provided with a call-locating device adapted to be made temporarily individual to any called subscriber thereof, to prevent disconnection between the subscribers, provided with means for giving a signal.
12. In a telephone system, means by which the calling subscriber extends connection to the called line, means for releasing said connection controlled by a subscriber, and means for preventing the calling subscriber from controlling said releasing means.
13. In a telephone system, subscribers' lines, an automatic connector switch for connecting with a called line, a release magnet, a relay controlling normally closed contacts in the circuit of said release magnet, and means for operating said relay to open said release circuit when connection is made with a subscriber's line.
14. In a telephone system, subscribers' lines, an automatic connector switch for connecting with a called line, a release magnet, a relay controlling normally closed contacts in the circuit of said release magnet, and means for energizing said relay when connection is made with a called line.
15. In a telephone system, subscribers' lines, an automatic connector switch for connecting with a called line, a release magnet, a relay controlling normally closed contacts in the circuit of said release magnet, a circuit for said relay including a high resistance, and means for closing a parallel connection around said high resistance, whereby sufficient current passes through said relay to energize the same.
16. In a telephone system, subscribers' lines, an automatic connector switch for connecting with a called line, a release magnet, a relay controlling normally closed contacts in the circuit of said release magnet, a parallel connection, and a signal-controlling means in said parallel connection whereby an indication is given when a connection is made with a called line.
17. In a telephone system, subscribers' lines, a switch for connecting with any one of said lines, a release magnet therefor, a relay for controlling the circuit of said release magnet, a switch individual to a subscriber's line, and an energizing circuit for said relay including a second relay in said individual switch.
18. In a telephone system, subscribers' lines, a switch for connecting with any one of said lines, a release magnet therefor, a relay for controlling the circuit of said release magnet, a switch individual to a subscriber's line, a high resistance relay and a low resistance relay in said individual switch, and an energizing circuit for said first-mentioned relay including said last-mentioned relays in series.

19. In a telephone system, subscribers' lines, a switch for connecting with any one of said lines, a release magnet therefor, a relay for controlling the circuit of said release magnet, a switch individual to a subscriber's line, a high resistance relay and a low resistance relay in said individual switch, an energizing circuit for said first-mentioned relay including said last-mentioned relays in series, and a signal controlled by said low resistance relay whereby an indication is given when a connection is made with a called line.
20. In a telephone system, subscribers' lines divided into groups, an automatic connector switch having motion in one plane to select groups, and motion in a plane at right-angles thereto to find a line in the selected group, for connecting with a called line, a release magnet, a relay controlling normally closed contacts in the circuit of said release magnet, and means for operating said relay to open said release when connection is made with a subscriber's line.
21. In a telephone system, subscribers' lines divided into groups, an automatic connector switch having motion in one plane to select groups, and motion in a plane at right-angles thereto to find a line in the selected group, for connecting with a called line, a release magnet, a relay controlling normally closed contacts in the circuit of said release magnet, and means for energizing said relay when connection is made with a called line.
22. In a telephone system, subscribers' lines divided into groups, an automatic connector switch having motion in one plane to select groups, and motion in a plane at right-angles thereto to find a line in the selected group, for connecting with a called line, a release magnet, a relay controlling normally closed contacts in the circuit of said release magnet, a circuit for said relay including a high resistance, and means for closing a parallel connection around said high resistance, whereby sufficient current passes through said relay to energize the same.
23. In a telephone system, subscribers' lines divided into groups, an automatic connector switch having motion in one plane to select groups, and motion in a plane at right-angles thereto to find a line in the selected group, for connecting with a called line, a release magnet, a relay controlling normally closed contacts in the circuit of said release magnet, a parallel connection, and a signal-controlling means in said parallel connection whereby an indication is given when a connection is made with a called line.
24. In a telephone system, subscribers' lines divided into groups, a switch having motion in one plane to select groups, and motion in a plane at right-angles thereto to find a line in the selected group, for connecting with any one of said lines, a release magnet therefor, a relay for controlling the circuit of said release magnet, a switch individual to a subscriber's line, and an energizing circuit for said relay including a second relay in said individual switch.
25. In a telephone system, subscribers' lines divided into groups, a switch having motion in one plane to select groups, and motion in a plane at right-angles thereto to find a line in the selected group, for connecting with any one of said lines, a release magnet therefor, a relay for controlling the circuit of said release magnet, a switch individual to a subscriber's line, a high resistance relay and a low resistance relay in said individual switch, and an energizing circuit for said first-mentioned relay including said last-mentioned relays in series.
26. In a telephone system, subscribers' lines divided into groups, a switch having motion in one plane to select groups, and motion in a plane at right-angles thereto to find a line in the selected group, for connecting with any one of said lines, a release magnet therefor, a relay for controlling the circuit of said release magnet, a switch individual to a subscriber's line, a high resistance relay and a low resistance relay in said individual switch, an energizing circuit for said first-mentioned relay including said last-mentioned relays in series, and a signal controlled by said low resistance relay whereby an indication is given when a connection is made with a called line.

Signed by us at Chicago, Cook county, Illinois, this 30th day of November, 1906.

TALBOT G. MARTIN.
JOHN ERICKSON.
